UNITED STATES PATENT OFFICE

153,533

DESIGN FOR A CLOTHES TREE

Herman G. Liebner, Milwaukee, Wis.

Application March 31, 1947, Serial No. 138,057

Term of patent 3½ years

(Cl. D33—8)

To all whom it may concern:

Be it known that I, Herman G. Liebner, a citizen of the United States, residing at Milwaukee, in the county of Milwaukee and State of Wisconsin, have invented a new, original, and ornamental Design for Clothes Tree, of which the following is a description, reference being had to the accompanying drawing, forming a part thereof.

In the drawing:

Fig. 1 is a perspective view of a clothes tree, embodying my new design; and

Fig. 2 is an enlarged perspective view of the essential part thereof.

The dominant and characteristic features of my design are shown by means of solid lines in the drawing.

I claim:

The ornamental design for a clothes tree, substantially as shown and described.

HERMAN G. LIEBNER.
